(57) **CLAIM**

The ornamental design for a mobile phone, as shown and described.

DESCRIPTION

FIG. 1 is a front perspective view of the mobile phone showing our new design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof;
FIG. 8 is a rear perspective view thereof;
FIG. 9 is a front perspective view in a condition that the claimed design has been expanded completely;
FIG. 10 is a front view of FIG. 9
FIG. 11 is a rear view of FIG. 9
FIG. 12 is a left side view of FIG. 9
FIG. 13 is a right side view of FIG. 9
FIG. 14 is a top plan view of FIG. 9
FIG. 15 is a bottom plan view of FIG. 9; and,
FIG. 16 is a rear perspective view of FIG. 9.
The broken lines depict portions of the mobile phone that form no part of the claimed design.

1 Claim, 16 Drawing Sheets
